UNITED STATES PATENT OFFICE

GUSTAVE E. VILLARET, OF LEONIA, NEW JERSEY, ASSIGNOR TO MARKEL ELECTRIC PRODUCTS, INC., OF BUFFALO, NEW YORK, A CORPORATION OF NEW YORK

DESIGN FOR A VASE ELEMENT OF AN ELECTRIC-LIGHT FIXTURE

Application filed January 21, 1929. Serial No. 29,700. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for a Vase Element of an Electric-Light Fixture, of which the following is a specification, reference being had to the accompanying drawing, forming part thereof.

In said drawing:

Figure 1 is an elevation of a vase element of an electric light fixture embodying my new

design. In this figure half of the design is shown in full lines and the remaining half is shown in marginal outline by dot and dash lines.

Figure 2 is a top plan view of the same, a quarter sector of the base being shown in full lines and the remainder being shown in outline in dot and dash lines.

I claim:

The ornamental design for a vase element of an electric light fixture, substantially as shown and described.

GUSTAVE E. VILLARET.
